SIZING OR GRADING DEVICE

Lovic Ernest Ellis, Lakeland, Fla.

Application February 28, 1933, Serial No. 659,012

2 Claims. (Cl. 299—105)

This invention relates to devices for sizing or grading fruit, vegetables, nuts and the like and has as its primary object to provide a device of this character capable of a wide range of adjustments consisting of comparatively few parts, is positive and efficient in operation, and otherwise well adapted for the purpose designed.

The invention together with its numerous objects and advantages will be best understood from a study of the following description, taken in connection with the accompanying drawings wherein:

Figure 1 is a plan view of the device.

Figure 2 is a sectional elevational view showing the means for holding the shaft adjusting lever in position.

Figure 3 is a top plan view of the device certain parts being removed.

Figure 4 is a longitudinal sectional elevational view through the device.

Figure 5 is a plan view of a portion of a supporting annulus.

Figure 6 is a fragmentary vertical sectional elevational view showing certain details of construction to be hereinafter more fully referred to.

Figure 7 is an elevational view showing the manner of attaching the annulus to a supporting leg, a sizing plate being arranged in position on the annulus.

Figure 8 is a fragmentary plan view showing a bearing equipped slide together with support and guide means therefor.

Referring to the drawings by reference numerals it will be seen that a supporting structure is provided, and that the same includes a base ring 1 to which are secured the lower ends of a plurality of legs or standards 2 that support an annulus 3. The annulus 3 may be of any suitable material, preferably material of a ductile quality so as to permit distortion and reshaping thereof. The plate 3 on its under side has secured thereto a series of relatively spaced inverted U-shaped clamps 4 straddle the upper ends of the legs or standards 2 in a manner clearly shown in Figure 7. The sides of the clamps 4 are longitudinally slotted for accommodating fasteners such as bolts and nuts 5 to secure the clamps engaged with the legs or standards and the annulus 3 in a predetermined position and condition, that is to say, to secure the annulus 3 at the desired vertical adjustment and either in flat or spiral form. Manifestly to secure the plate 3 in spiral form the clamps 4 are vertically adjusted relative to one another.

Arranged concentrically of the post or legs 2

is an outer circular series of shorter standards 6 which have their intermediate portions connected by arcuate strips 7. Inclined pan supporting bars 8 are secured at their lower ends to the standards 6 and at their upper ends to the rim of a spider 9. The bars 7 and 8 provide inclined supports for pans 10.

Supported by certain of the legs or standards 2 adjacent the lower ends thereof are cross bars 11 which provide a support for a stepped slide or block member 12 constrained to shift between a pair of spaced parallel guides 13.

Each stepped portion of the block 12 as shown in Figures 6 and 8 is provided with a bearing 14 and any one of the bearings will readily accommodate the lower end of a vertical driven shaft 15. Shaft 15 as shown in Figure 6 also extends upwardly through the hub of the spider 9, and mounted on the upper end of the shaft for rotation therewith is a distributor member 16.

The distributor member 16 may be formed of any material, and be of any desired shape or construction; however in the present instance I have shown the same as being in the nature of a wheel.

Supported by the annulus 3 is a circular series 25 of segmental sizing or grading plates 17. Plates 17 may be of any suitable construction and formed from any suitable material it being preferable however to have the top face of each plate disposed at an incline sloping inwardly from the outer to the inner edge thereof as shown. In the present instance each plate 17 is provided on its under side with a depending flange or web 18 for supporting the plate 17 at an incline. Each plate 17 is also provided with a depending bolt 35 19 having a nut suitably engaged therewith, and the bolts 19 of the plates operate in slots 20 provided therefor in the plate 3 whereby provision is made for adjusting the plates radially with reference to the plate or annulus 3 and wheel 16. 40

To raise or lower the shaft 15 to adjust the distributor element 16 in a vertical plane relative to the plate 3 and grading plates 17 there is provided a lever 21 pivotally mounted adjacent one end on a standard 22 and provided at said one end with a fork 23 engaging a grooved collar 24 provided on the shaft 15. Adjacent the handle equipped end thereof the lever 21 operates in a guide bracket 25 mounted on one of the legs or standards 2 as clearly shown in Figure 2. On the inner side thereof the guide 25 is provided with a vertical series of spaced ratchet like teeth or lugs 26 providing abutments to be selectively engaged by the handle 21 for holding the shaft 15 in a raised position until 55

the proper one of the bearings 14 is moved into position for receiving the lower end of the shaft. The slide block 12 carrying the bearings 14 is provided with a handle 27 to facilitate manipulation thereof. Handle 27 also operates in a guide 28 provided therefor on one of the legs or stands 2.

Any suitable means may be employed for driving the shaft 15 and in the present instance 10 there is provided a horizontal shaft 29 journaled in bearings 30, 31 carried by standards 6, 2 and a bearing standard 32. On its inner end the shaft 29 is provided with a bevel gear 33 while on its outer end the shaft is provided with a 15 pulley 34 so that a belt and pulley drive connection may be readily made between the shaft 29 and the shaft of a prime mover or any other suitable source of power. A gear 35 is mounted on the shaft 15 and a set screw or the like is 20 provided for securing the gear 35 at the desired longitudinal adjustment relative to the shaft 15 so as to be properly positioned to mesh with the gear 33 subsequent to an adjustment of the shaft 15. Manifestly when power is transmitted to 25 shaft 29, drive is transmitted therefrom to shaft 15 through the medium of the intermeshing gears 33, 35.

The operation of the device is thought clear from the above. The fruit, vegetables, or nuts 30 to be graded are placed on the sizing plates 17 after proper adjustments of the distributor 16, plates 17 and annulus 3 have been made. As the distributor 16 revolves the fruit, vegetables or nuts as the case may be by contact with the 35 periphery of the distributor 16 are distributed over the plates 17 in a manner to permit the fruit, vegetables or nuts of a proper size to pass from the plates 17 through the space between said plates and the distributor 16 into the pans 40 10 provided for receiving same.

It will be apparent that various adjustments may be made from time to time and that an efficient grading of the fruits, vegetables, nuts or the like will be assured under almost any and all conditions.

5

Even though I have herein shown and described the preferred embodiment of the invention, it is to be understood that the same is susceptible of further changes, modifications and improvements coming within the scope of the 10 appended claims.

Having thus described my invention, what I claim as new is:

1. In a grading device of the character described, an annular ductile supporting plate, a 15 support therefor, and connections between the plate and its support for securing the plate on the support in either a normal or distorted condition optionally; a revoluble element supported above and substantially concentrically to said plate, and grading plates supported by the first named plate and adjustable thereon radially to the revoluble element, means for securing the last named plates at the desired adjustment, and said last named plates having inclined surfaces upon which the fruit rests.

2. In a fruit grader, a substantially circular supporting structure, an annular ductile plate supported by said structure, connections between said plate and said supporting structure for securing the plate at the desired vertical adjustment and in either a normal or predetermined distorted condition, optionally; grading plates carried by the annular plate and presenting an inclined fruit supporting surface for the first named plate, and revoluble means for advancing the fruit over said surface and against the peripheral edge of which the fruit bears.

LOVIC EARNEST ELLIS.
